UNITED STATES PATENT OFFICE

2,341,171

MAGNETIC FLUX DISTRIBUTOR

Alessandro Alessandri, Milan, Italy; vested in
the Alien Property CustodianApplication July 24, 1940, Serial No. 347,313
In Italy July 31, 1939

6 Claims. (Cl. 171—209)

It is known that laminated members consisting of ferromagnetic sheets are used in electromagnetic apparatus and particularly in ignition magnetos for internal combustion engines to convey or distribute a variable magnetic flux. In such members it is essential to avoid the formation of short-circuit paths causing large losses due to eddy currents.

This invention is directed to members of such class in which losses by eddy currents are avoided and satisfactory conditions of operation are secured with respect both to the conveyance of magnetic flux and the machining of the parts.

This invention includes laminated members having connecting members to assemble the sheets and extending transversely to said sheets, and which are located substantially in one and the same plane parallel to the path of the magnetic flux in the member.

On the other hand the laminated members embodied in the device and whose connecting members are in condition to provide short-circuit paths extending through several members, are separated from each other by gaps intersecting said paths.

This invention further includes the provision of flux distributors by means of members built up in accordance with this invention which are arranged to provide sections arranged radially and longitudinally with respect to the distributor axis respectively, in satisfactory condition both as to the provision of the distributor and the distribution and conveyance of the magnetic flux.

An embodiment of this invention in a flux distributor for an ignition magneto of an internal combustion engine is shown by way of example on the annexed drawings in which:

Fig. 1 is a fragmentary longitudinal section of an ignition magneto provided with a flux distributor in accordance with this invention said section being made on the section line 1—1 of Fig. 2;

Fig. 2 is a transverse section thereof on section line 2—2 of Fig. 1 with parts removed, and illustrates one of the distributor star members and the transverse section of the distributor core; and,

Fig. 3 is a partially schematic showing of the magnetic members with parts broken away so that a typical magnetic circuit may be followed.

In the illustrated embodiment the magneto includes a shaft 1 journaled in bearings 2 and 3 fast in the magneto casing 4 in which a stationary ring-shaped magnet 5 and a winding including a primary section 6 and a secondary section

7 are located, said winding 6—7 encircling a portion of the shaft 1. Flux conveying rods 8 extend longitudinally from the poles of the magnet 5 and a flux distributor, as hereinafter described, cooperates with said rods 8 to produce variations in the magnetic flux interlinking with the winding 6—7 to generate induced electromotive forces. A circuit breaker, not shown, actuated by the magneto shaft 1, is operative in the circuit of the primary section 6 of the winding 6, 7 the secondary section 7 supplying high voltage to a high voltage distributor (not shown) and to cables leading from said distributor to engine sparking plugs. The breaker and high voltage distributor driven by the shaft 1 are not shown and may be of any approved or conventional type.

The flux distributor is fixed to the shaft 1 and includes a hollow cylindrical core denoted in its whole by 9 and embracing the shaft 1 and connected with it in rotation, said core extending throughout the winding 6, 7. The flux distributor also includes two end stars 10, 11 extending transversely beyond the ends of the winding 6, 7 and providing spaced arms 10', 11' arranged at an angle from each other to provide, in cooperation with the core 9 and the rods 8, the requisite magnetic paths interconnecting the poles of the magnet 5 and to cause variations in the value of the flux flowing through the core 9 and interlinking with the winding section 6 to generate an induced electromotive force.

As illustrated, each star 10, 11 of the flux distributor includes a head 12 of non-magnetic material which is fast with a flange 22 of the shaft 1 and a laminated ferromagnetic member 13 shaped to provide annular rim sections 10'', 11'' each having a radially extending arm 10', 11'. Each laminated member 13 is fastened on the head 12 by means of a plate 14 and rivets 15.

In accordance with this invention the rivets 15 embodied in each rim section and arms 10', 10'', 11', 11'' are located in a plane having a diametrical location with respect to the shaft 1 and the whole of stars 10, 11. The rim sections 10'', 11'' of each star are segment shaped and are separated from each other by means of radial gaps 16 in the region of said member 13 which are included between adjacent arms. The gaps 16 also intersect the fastening plates 14.

The described arrangement prevents any short-circuiting path in the stars 10, 11 because the rivets 15 of each rim section and arms 10', 10'', 11', 11'' are located in a plane parallel with the path of the flux through the concerned rim section and arm and such paths as provided by head

12, rivets 15, laminated member 13 and plate 14 do not intersect the flux lines extending through the concerned rim section and arm. On the other hand the gaps 16 separating the several sections of each star 10, 11 intersect such short-circuiting paths as would be provided by the rivets 15 of sections as 10', 10'', 11', 11'' adjacent to each other in each star 10, 11.

10 The assembly of the several sections of the flux distributor is provided by the fact that each section is connected by means of rivets 15 to the cooperating shaft head 12.

15 The central core 9 of the distributor which interconnects the two stars 10, 11 and extends throughout the winding 6, 7, is provided with longitudinal rods 17, each of which includes a laminated ferromagnetic member 18 embraced by two strips 19. Their assembly is secured by flat rivets 20. The ends of the rods 17 enter the internal apertures provided in the rim sections 10', 11'' of the stars 10, 11 and said rods 17 are clamped intermediate the two heads 12 of the distributor.

20 The laminations 18 are parallel to each other in each longitudinal rod 17 and each rod 17 is shaped to be symmetrical with respect to a middle longitudinal plane extending through its middle line $x-x$ (Fig. 2). This line, when the rod 17 is assembled in the distributor, lies in a diametrical position with respect to the axis of the shaft 1. Best conditions are thus secured both in respect of machining of the rods 17 and in respect of the flow of the flux throughout the stars 10, 11 and rods 17 because by the effect of the above described provision the edges of all the laminations 18 are substantially radial to the axis of the core 9 consisting of the assembly of the rods 17 and consequently they are substantially perpendicular to the tool in the lathe during machining of the core as well as to the surface of contact with the star rim sections 10', 11'' when said core is assembled with the stars 10, 11.

25 The rivets 20 interconnecting the laminations 18 and the side strips 19 of each rod 17 cannot cause short circuit paths because they are aligned in the direction of the flux. Such paths as could be provided in the transverse section of the core 9 by the strips 19 and the rivets 20 are cut by means of a gap 21 provided between two adjacent rods 17 and strip 19 (Fig. 2).

30 The provision of the stars 10, 11 and of the core 9 by means with segmental sections 10', 10'', 11', 11'' and 17 respectively, as above described, further secures the advantage that the flow of the flux through the laminations of the stars 10, 11 and the laminations 18 of rods 17 of the core 9 is made uniform. In fact apart from the fact that the flow of the flux is uniform in respect of each rod 17 due to the substantially radial location of all the laminations 18 of the concerned rod, the separation of the stars 10, 11 in separate segmental sections 10', 10'' and 11', 11'' in register with several arms 10', 11' causes the flux flowing through each arm 10', 11' to follow a radial direction in the core 9. Consequently any unevenness in the flux distribution and any flux dispersion around the core 9 as could arise from uneven gaps between the several sections 10', 10'', 11', 11'' and cooperating rods 17 of the core 9, are avoided.

35 A magneto equipped with the described flux distributor operates in the usual well known manner. In Fig. 3, a typical magnetic circuit is traced by a heavy broken line. This line extends from the south pole marked "S" near the bottom of the

40 figure along the rod 8 to the star 10 and thence toward the axis to the core rod 17. The circuit is completed through the core rod 17 to star 11 and thence outwardly to the adjacent rod 8 and back to the north pole marked "N." The rotation of the flux distributor 10, 9, 11 when driven by the shaft 1 in cooperation with the magnet 5 and the flux conveying rods 8 causes periodical variations in the value of the flux which flows through the core rods 17 and interlinks with the primary winding section 6. The operation of the breaker inserted in the circuit of the winding section 6 generates high voltage induced electro-motive forces in the winding section 7 which are supplied to the engine sparking plugs as well known.

45 What I claim as my invention and desire to secure by United States Letters Patent is:

1. In an electromagnetic apparatus, a magnetic flux distributor comprising a non-magnetic support plate, ferro-magnetic laminated members on said support plate around the center thereof and each consisting of superimposed sheets located parallel with said plate and comprising an arc-shaped portion concentric with said plate and a portion extending radially from said arc-shaped portion, said members being arranged annularly around the center of said plate and being separated from each other by intervening gaps, and a plurality of connecting members assembling said sheets of each of said laminated members with each other and with said supporting plate, said connecting members being located in a plane perpendicular to said supporting plate and sheets and extending through the middle radius of said radially extending portion of the respective laminated member.

50 2. In an electromagnetic apparatus, a magnetic flux distributor comprising a core consisting of laminated ferromagnetic rods arranged around an axis and extending parallel with and along said axis, each of said rods consisting of sheets lying in planes substantially parallel with each other and the middle one of said sheets in said rod lying in a plane passing through said axis, connecting members assembling the sheets of each of said rods, star members each at one of the ends of said core and including a non-magnetic support plate transverse to said axis and separate ferromagnetic laminated members on said support plate, each consisting of superimposed sheets comprising an arc-shaped portion concentric with said plate and a portion extending radially from said arc-shaped portion, said sheets being located parallel to said plate and a plurality of connecting members assembling said sheets of each of said laminated members with each other and with said support plate, said last named connecting members being located in a plane perpendicular to said supporting plate and sheets and extending through the middle radius of said radially extending portion of the respective laminated member.

55 3. In an electromagnetic apparatus, a magnetic flux distributor comprising a core consisting of laminated ferromagnetic rods arranged around an axis and extending parallel with and along said axis, each of said rods consisting of sheets lying in planes substantially parallel to each other and the middle one of said sheets in said rod lying in a plane passing through said axis, connecting members assembling the sheets of each of said rods, annular star members each embracing one of the ends of said core and including a non-magnetic annular support plate

transverse to said axis and separate ferromagnetic laminated members on said annular support plate and contacting with said rods, each of said laminated members consisting of superimposed sheets comprising an arc-shaped portion concentric with said plate and a portion extending radially from said arc-shaped portion, said sheets being located parallel to said plate and a plurality of connecting members assembling said sheets of each of said laminated members with each other and with said support plate, said last named connecting members being located in a plane perpendicular to said supporting plate and sheets and extending through the middle radius of said radially extending portion of the respective laminated member.

4. In an electromagnetic apparatus, a magnetic flux distributor comprising ferro-magnetic laminated members each comprising superimposed sheets, said members being arranged annularly around and extending radially from the axis of said distributor and being magnetically separated from each other by gaps and connecting members assembling said sheets of each of

said members with each other, said connecting members being located in a plane extending through the middle radius of said laminated member.

5. In an electromagnetic apparatus, a magnetic flux distributor comprising a core comprising laminated ferro-magnetic rods arranged close to each other around an axis and extending parallel with and along said axis, each of said rods being separated from the adjacent rods by a gap, and each of said rods consisting of sheets lying in planes substantially parallel with each other and the middle one of said sheets in said rod lying in a plane passing through said axis and connecting members assembling said sheets of each of said rods and positioned transverse to said sheets.

6. Apparatus as described in claim 5 wherein said connecting members are in the form of flat rivets which extend lengthwise transversely of the sheets and which have their width dimensions extending longitudinally of the rods.

ALESSANDRO ALESSANDRI.
